(57) **CLAIM**

The ornamental design for a sprinkler, as shown and described.

DESCRIPTION

FIG. 1 is a top perspective view of a sprinkler design showing my new design.

FIG. 2 is a front view of a sprinkler.

FIG. 3 is a rear view of a sprinkler.

FIG. 4 is a left side view of a sprinkler.

FIG. 5 is a right side view of a sprinkler.

FIG. 6 is a top view of a sprinkler.

FIG. 7 is a bottom view of a sprinkler.

FIG. 8 is a bottom perspective view of a sprinkler.

FIG. 9 is an enlarged detail view taken from portion 9 of FIG. 1; and,

FIG. 10 is an enlarged detail view taken from portion 10 of FIG. 1.

Shade lines shown represent surface contours and not surface ornamentation.

The dashed broken lines depict portions of the sprinkler that form no part of the claim.
